CLAIM

The ornamental design for a side wall for a drawer, as shown and described.

DESCRIPTION

- FIG. 1 is a front view of a side wall for a drawer, showing a first embodiment of my new design;
 FIG. 2 is a rear view thereof;
 FIG. 3 is a right side view thereof;
 FIG. 4 is a left side view thereof;
 FIG. 5 is a top view thereof;
 FIG. 6 is a bottom view thereof;
 FIG. 7 is a right perspective view thereof;
 FIG. 8 is a front view of a side wall for a drawer, showing a second embodiment of my new design;
 FIG. 9 is a rear view thereof;
 FIG. 10 is a right side view thereof;
 FIG. 11 is a left side view thereof;
 FIG. 12 is a top view thereof;
 FIG. 13 is a bottom view thereof;

- FIG. 14 is a right perspective view thereof;
 FIG. 15 is a front view of a side wall for a drawer, showing a third embodiment of my new design;
 FIG. 16 is a rear view thereof;
 FIG. 17 is a right side view thereof;
 FIG. 18 is a left side view thereof;
 FIG. 19 is a top view thereof;
 FIG. 20 is a bottom view thereof;
 FIG. 21 is a right perspective view thereof;
 FIG. 22 is a front view of a side wall for a drawer, showing a fourth embodiment of my new design;
 FIG. 23 is a rear view thereof;
 FIG. 24 is a right side view thereof;
 FIG. 25 is a left side view thereof;
 FIG. 26 is a top view thereof;
 FIG. 27 is a bottom view thereof;
 FIG. 28 is a right perspective view thereof;
 FIG. 29 is a front view of a side wall for a drawer, showing a fifth embodiment of my new design;
 FIG. 30 is a rear view thereof;
 FIG. 31 is a right side view thereof;
 FIG. 32 is a left side view thereof;
 FIG. 33 is a top view thereof;
 FIG. 34 is a bottom view thereof;
 FIG. 35 is a right perspective view thereof;
 FIG. 36 is a front view of a side wall for a drawer, showing a sixth embodiment of my new design;
 FIG. 37 is a rear view thereof;
 FIG. 38 is a right side view thereof;
 FIG. 39 is a left side view thereof;
 FIG. 40 is a top view thereof;
 FIG. 41 is a bottom view thereof;
 FIG. 42 is a right perspective view thereof;
 FIG. 43 is a front view of a side wall for a drawer, showing a seventh embodiment of my new design;
 FIG. 44 is a rear view thereof;
 FIG. 45 is a right side view thereof;
 FIG. 46 is a left side view thereof;
 FIG. 47 is a top view thereof;
 FIG. 48 is a bottom view thereof;
 FIG. 49 is a right perspective view thereof;
 FIG. 50 is a front view of a side wall for a drawer, showing an eighth embodiment of my new design;
 FIG. 51 is a rear view thereof;
 FIG. 52 is a right side view thereof;
 FIG. 53 is a left side view thereof;
 FIG. 54 is a top view thereof;
 FIG. 55 is a bottom view thereof;
 FIG. 56 is a right perspective view thereof;
 FIG. 57 is a front view of a side wall for a drawer, showing a ninth embodiment of my new design;
 FIG. 58 is a rear view thereof;
 FIG. 59 is a right side view thereof;
 FIG. 60 is a left side view thereof;
 FIG. 61 is a top view thereof;
 FIG. 62 is a bottom view thereof;
 FIG. 63 is a right perspective view thereof;
 FIG. 64 is a front view of a side wall for a drawer, showing a tenth embodiment of my new design;
 FIG. 65 is a rear view thereof;
 FIG. 66 is a right side view thereof;
 FIG. 67 is a left side view thereof;
 FIG. 68 is a top view thereof;
 FIG. 69 is a bottom view thereof;
 FIG. 70 is a right perspective view thereof;

FIG. 71 is a front view of a side wall for a drawer, showing an eleventh embodiment of my new design;
FIG. 72 is a rear view thereof;
FIG. 73 is a right side view thereof;
FIG. 74 is a left side view thereof;
FIG. 75 is a top view thereof;
FIG. 76 is a bottom view thereof;
FIG. 77 is a right perspective view thereof;
FIG. 78 is a front view of a side wall for a drawer, showing a twelfth embodiment of my new design;
FIG. 79 is a rear view thereof;
FIG. 80 is a right side view thereof;
FIG. 81 is a left side view thereof;
FIG. 82 is a top view thereof;
FIG. 83 is a bottom view thereof;
FIG. 84 is a right perspective view thereof;
FIG. 85 is a front view of a side wall for a drawer, showing a thirteenth embodiment of my new design;
FIG. 86 is a rear view thereof;
FIG. 87 is a right side view thereof;
FIG. 88 is a left side view thereof;
FIG. 89 is a top view thereof;
FIG. 90 is a bottom view thereof;
FIG. 91 is a right perspective view thereof;
FIG. 92 is a front view of a side wall for a drawer, showing a fourteenth embodiment of my new design;
FIG. 93 is a rear view thereof;
FIG. 94 is a right side view thereof;
FIG. 95 is a left side view thereof;
FIG. 96 is a top view thereof;
FIG. 97 is a bottom view thereof;
FIG. 98 is a right perspective view thereof;
FIG. 99 is a front view of a side wall for a drawer, showing a fifteenth embodiment of my new design;
FIG. 100 is a rear view thereof;
FIG. 101 is a right side view thereof;
FIG. 102 is a left side view thereof;
FIG. 103 is a top view thereof;
FIG. 104 is a bottom view thereof;
FIG. 105 is a right perspective view thereof;
FIG. 106 is a front view of a side wall for a drawer, showing a sixteenth embodiment of my new design;
FIG. 107 is a rear view thereof;
FIG. 108 is a right side view thereof;
FIG. 109 is a left side view thereof;
FIG. 110 is a top view thereof;
FIG. 111 is a bottom view thereof;
FIG. 112 is a right perspective view thereof;
FIG. 113 is a front view of a side wall for a drawer, showing a seventeenth embodiment of my new design;
FIG. 114 is a rear view thereof;
FIG. 115 is a right side view thereof;
FIG. 116 is a left side view thereof;
FIG. 117 is a top view thereof;
FIG. 118 is a bottom view thereof;
FIG. 119 is a right perspective view thereof;
FIG. 120 is a front view of a side wall for a drawer, showing an eighteenth embodiment of my new design;
FIG. 121 is a rear view thereof;
FIG. 122 is a right side view thereof;
FIG. 123 is a left side view thereof;
FIG. 124 is a top view thereof;
FIG. 125 is a bottom view thereof;
FIG. 126 is a right perspective view thereof;

FIG. 127 is a front view of a side wall for a drawer, showing a nineteenth embodiment of my new design;
FIG. 128 is a rear view thereof;
FIG. 129 is a right side view thereof;
FIG. 130 is a left side view thereof;
FIG. 131 is a top view thereof;
FIG. 132 is a bottom view thereof;
FIG. 133 is a right perspective view thereof;
FIG. 134 is a front view of a side wall for a drawer, showing a twentieth embodiment of my new design;
FIG. 135 is a rear view thereof;
FIG. 136 is a right side view thereof;
FIG. 137 is a left side view thereof;
FIG. 138 is a top view thereof;
FIG. 139 is a bottom view thereof;
FIG. 140 is a right perspective view thereof;
FIG. 141 is a front view of a side wall for a drawer, showing a twenty-first embodiment of my new design;
FIG. 142 is a rear view thereof;
FIG. 143 is a right side view thereof;
FIG. 144 is a left side view thereof;
FIG. 145 is a top view thereof;
FIG. 146 is a bottom view thereof;
FIG. 147 is a right perspective view thereof;
FIG. 148 is a front view of a side wall for a drawer, showing a twenty-second embodiment of my new design;
FIG. 149 is a rear view thereof;
FIG. 150 is a right side view thereof;
FIG. 151 is a left side view thereof;
FIG. 152 is a top view thereof;
FIG. 153 is a bottom view thereof;
FIG. 154 is a right perspective view thereof;
FIG. 155 is a front view of a side wall for a drawer, showing a twenty-third embodiment of my new design;
FIG. 156 is a rear view thereof;
FIG. 157 is a right side view thereof;
FIG. 158 is a left side view thereof;
FIG. 159 is a top view thereof;
FIG. 160 is a bottom view thereof;
FIG. 161 is a right perspective view thereof;
FIG. 162 is a front view of a side wall for a drawer, showing a twenty-fourth embodiment of my new design;
FIG. 163 is a rear view thereof;
FIG. 164 is a right side view thereof;
FIG. 165 is a left side view thereof;
FIG. 166 is a top view thereof;
FIG. 167 is a bottom view thereof;
FIG. 168 is a right perspective view thereof;
FIG. 169 is a front view of a side wall for a drawer, showing a twenty-fifth embodiment of my new design;
FIG. 170 is a rear view thereof;
FIG. 171 is a right side view thereof;
FIG. 172 is a left side view thereof;
FIG. 173 is a top view thereof;
FIG. 174 is a bottom view thereof;
FIG. 175 is a right perspective view thereof;
FIG. 176 is a front view of a side wall for a drawer, showing a twenty-sixth embodiment of my new design;
FIG. 177 is a rear view thereof;
FIG. 178 is a right side view thereof;
FIG. 179 is a left side view thereof;
FIG. 180 is a top view thereof;
FIG. 181 is a bottom view thereof;
FIG. 182 is a right perspective view thereof;

FIG. 183 is a front view of a side wall for a drawer, showing a twenty-seventh embodiment of my new design;
FIG. 184 is a rear view thereof;
FIG. 185 is a right side view thereof;
FIG. 186 is a left side view thereof;
FIG. 187 is a top view thereof;
FIG. 188 is a bottom view thereof;
FIG. 189 is a right perspective view thereof;
FIG. 190 is a front view of a side wall for a drawer, showing a twenty-eighth embodiment of my new design;
FIG. 191 is a rear view thereof;
FIG. 192 is a right side view thereof;
FIG. 193 is a left side view thereof;
FIG. 194 is a top view thereof;
FIG. 195 is a bottom view thereof;
FIG. 196 is a right perspective view thereof;
FIG. 197 is a front view of a side wall for a drawer, showing a twenty-ninth embodiment of my new design;
FIG. 198 is a rear view thereof;
FIG. 199 is a right side view thereof;
FIG. 200 is a left side view thereof;
FIG. 201 is a top view thereof;
FIG. 202 is a bottom view thereof;
FIG. 203 is a right perspective view thereof;
FIG. 204 is a front view of a side wall for a drawer, showing a thirtieth embodiment of my new design;
FIG. 205 is a rear view thereof;
FIG. 206 is a right side view thereof;
FIG. 207 is a left side view thereof;
FIG. 208 is a top view thereof;
FIG. 209 is a bottom view thereof;
FIG. 210 is a right perspective view thereof;
FIG. 211 is a front view of a side wall for a drawer, showing a thirty-first embodiment of my new design;
FIG. 212 is a rear view thereof;
FIG. 213 is a right side view thereof;
FIG. 214 is a left side view thereof;
FIG. 215 is a top view thereof;
FIG. 216 is a bottom view thereof;
FIG. 217 is a right perspective view thereof;
FIG. 218 is a front view of a side wall for a drawer, showing a thirty-second embodiment of my new design;
FIG. 219 is a rear view thereof;
FIG. 220 is a right side view thereof;
FIG. 221 is a left side view thereof;
FIG. 222 is a top view thereof;
FIG. 223 is a bottom view thereof;
FIG. 224 is a right perspective view thereof;
FIG. 225 is a front view of a side wall for a drawer, showing a thirty-third embodiment of my new design;
FIG. 226 is a rear view thereof;
FIG. 227 is a right side view thereof;
FIG. 228 is a left side view thereof;
FIG. 229 is a top view thereof;
FIG. 230 is a bottom view thereof;
FIG. 231 is a right perspective view thereof;
FIG. 232 is a front view of a side wall for a drawer, showing a thirty-fourth embodiment of my new design;

FIG. 233 is a rear view thereof;
FIG. 234 is a right side view thereof;
FIG. 235 is a left side view thereof;
FIG. 236 is a top view thereof;
FIG. 237 is a bottom view thereof;
FIG. 238 is a right perspective view thereof;
FIG. 239 is a front view of a side wall for a drawer, showing a thirty-fifth embodiment of my new design;
FIG. 240 is a rear view thereof;
FIG. 241 is a right side view thereof;
FIG. 242 is a left side view thereof;
FIG. 243 is a top view thereof;
FIG. 244 is a bottom view thereof;
FIG. 245 is a right perspective view thereof;
FIG. 246 is a front view of a side wall for a drawer, showing a thirty-sixth embodiment of my new design;
FIG. 247 is a rear view thereof;
FIG. 248 is a right side view thereof;
FIG. 249 is a left side view thereof;
FIG. 250 is a top view thereof;
FIG. 251 is a bottom view thereof;
FIG. 252 is a right perspective view thereof;
FIG. 253 is a front view of a side wall for a drawer, showing a thirty-seventh embodiment of my new design;
FIG. 254 is a rear view thereof;
FIG. 255 is a right side view thereof;
FIG. 256 is a left side view thereof;
FIG. 257 is a top view thereof;
FIG. 258 is a bottom view thereof;
FIG. 259 is a right perspective view thereof;
FIG. 260 is a front view of a side wall for a drawer, showing a thirty-eighth embodiment of my new design;
FIG. 261 is a rear view thereof;
FIG. 262 is a right side view thereof;
FIG. 263 is a left side view thereof;
FIG. 264 is a top view thereof;
FIG. 265 is a bottom view thereof;
FIG. 266 is a right perspective view thereof;
FIG. 267 is a front view of a side wall for a drawer, showing a thirty-ninth embodiment of my new design;
FIG. 268 is a rear view thereof;
FIG. 269 is a right side view thereof;
FIG. 270 is a left side view thereof;
FIG. 271 is a top view thereof;
FIG. 272 is a bottom view thereof;
FIG. 273 is a right perspective view thereof;
FIG. 274 is a front view of a side wall for a drawer, showing a fortieth embodiment of my new design;
FIG. 275 is a rear view thereof;
FIG. 276 is a right side view thereof;
FIG. 277 is a left side view thereof;
FIG. 278 is a top view thereof;
FIG. 279 is a bottom view thereof; and,
FIG. 280 is a right perspective view thereof.

The even dashed broken lines shown in the drawings represent portions of the side wall for a drawer that form no part of the claimed design.
